UNITED STATES PATENT OFFICE.

MILLER REESE HUTCHISON, OF NEW YORK, N. Y., ASSIGNOR TO LOVELL-McCONNELL MANUFACTURING COMPANY, A CORPORATION OF DELAWARE.

MECHANICALLY-ACTUATED HORN OR ALARM.

1,170,158.

Specification of Letters Patent.

Patented Feb. 1, 1916.

Application filed June 7, 1910. Serial No. 565,564.

To all whom it may concern:

Be it known that I, MILLER REESE HUTCHISON, a citizen of the United States, and resident of the city of New York, in the county of New York and State of New York, have invented certain new and useful Improvements in Mechanically-Actuated Horns or Alarms, of which the following is a specification.

- 10 My present invention relates to alarms, signals, horns etc., wherein the sound is produced by a mechanically vibrated diaphragm. It involves a broadly novel apparatus wherein the intermittent or vibratory 15 movement for mechanically agitating the diaphragm, is generated by relative movement of friction surfaces of such nature and in such relation that internally originated, uniformly recurrent grips and releases are 20 automatically set up. This intermittent grip and slip action between the relatively moving friction surfaces is applied to vibrate the diaphragm. The sounds produced may be more or less musical, and may be loud 25 and penetrating so as to render the device very efficient as an alarm or signal. The friction surfaces have preferably, though not necessarily a high coefficient of friction, and are of such a character that relatively 30 slight variations of intimacy of contact cause relatively enormous variations of friction so that when they are relatively moved in yielding contact, they tend alternately to acquire great intimacy of contact, with enormous friction, causing driving and driven 35 member to move together, and then when increasing tension on the driven member causes a slight separation or variation of intimacy of contact of the surfaces, to cause 40 an enormous decrease in the friction. In the extreme case the grip action is practically perfect and the succeeding slip is practically free and frictionless. In accordance with the preferred forms of the present invention 45 one of the friction surfaces is formed on a rotor and the other on an intermittent grip member which is yieldingly or resiliently supported, as by being connected to the resilient diaphragm or by connection to 50 the diaphragm and another resilient support, or otherwise. When the rotor is started, the grip member, being held or brought against the surface thereof by suitable means, travels with the rotor, until the mo-

ment when the increasing tension of the diaphragm, or other force opposing the tractive effort, destroys the exceedingly intimate union between the rotor and grip member. The rotor continues, and the slight separation due to this relative slip between the surfaces, causes a great and instantaneous drop in the amount of friction, so that the friction may be said to be almost annihilated for the moment. Consequently, the grip member, instead of either following the rotor, or remaining stationary with the rotor traveling beneath it, jumps back at high velocity under the influence of the tension of the diaphragm or other force. The surfaces now grip again, the intimacy of contact is restored, and the grip member is again drawn forward, to be again released. The frequency and length of the slips, and consequently the frequency and amplitude of vibration, will vary according to the particular friction surfaces selected, the speed of the rotor, the degree of pressure holding the surfaces together, the elasticity of the diaphragm or the effective magnitude of the force tending to produce the retrograde slip of the grip member, and the inertia of the parts to be moved; but the presence of a sort of grip and slip or "chattering" phenomenon, however such phenomenon may be modified by the conditions enumerated, is preferably attained by the use of friction surfaces having the properties described. A wide range of surfaces may be selected from amber and hard rubber, wrought iron and hard rubber, wrought iron and rawhide, steel or bronze and catgut, and non-lubricated surfaces of the same metal of about the relative smoothness or roughness produced by the emery wheel, may be used as friction "couples" for the production of the grips and slips. Many other surfaces may be used. The surfaces may be produced by applying powdered resin to surfaces which would otherwise not possess the required properties; or by the use of resin the grip and slip action of surfaces within the class may be greatly increased. Polishing and lubrication tend to decrease development of the phenomenon so that with the other variable factors above mentioned the desired action may always be secured. Friction surfaces of such a character or contacting in such relation or under such conditions as to

produce the grip and slip or chattering action must be clearly distinguished from those by the use of which no such phenomenon would be produced, as for instance where lubrication of parts or their geometrical relation is such that the grip member tends to remain in a position of equilibrium on the traveling rotor under the opposed forces of the tension of the resilient support on the one hand and the tractive effort of the rotor on the other. The frequency and length of the slips of the grip member as determined by the above enumerated factors may be further controlled by using a diaphragm having a natural frequency of vibration corresponding to the note to be produced, and if a heavy resonator or horn be employed this resonator may impose its natural period on the diaphragm; so that the sound will be produced primarily by the gripping and slipping of the friction surfaces, but the resonator and diaphragm may have a reactive effect in controlling the frequency of these grips and slips, and also in increasing the amplitude of the oscillatory or reciprocatory grip and slip movements. The grip member may also have an appreciable movement toward and from the rotor under the influence of the vibrations of the diaphragm and where a pronounced chattering is produced as between hard metal surfaces, the movement toward and from the rotor may be considerable as compared with the movement along the surface of the rotor.

The invention is capable of embodiment in and performance with many different structural forms and arrangements. In the accompanying drawings are illustrated a few of these.

In the said drawings: Figure 1 is a view partly in vertical section and partly in elevation of one form of the invention; Fig. 2 is a front view with the resonator and front part of the diaphragm casing removed; Fig. 3 is a sectional plan view of the rotor, brake-shoe, central portion of the diaphragm and connected parts; Fig. 4 is a detail plan view of the brake-shoe; Fig. 5 is a sectional elevation of another form of the invention; Fig. 6 is a detail thereof; Fig. 7 is a sectional elevation of another form of the invention; Fig. 8 is a sectional plan of the operative parts shown in Fig. 7; Fig. 9 is a sectional elevation of another form of the invention; Fig. 10 is a sectional elevation of another form of the invention; Fig. 11 is a sectional plan view of the operative parts shown in Fig. 10; and Fig. 12 is a sectional plan view of another form of the invention.

The rotor is driven by suitable power means, preferably a rotary motor, and preferably an electric motor. Of electric motors, I prefer to use those that run on direct current and at low voltage, preferably 4 to 6

volts, so that the motor may be supplied by the regular sparking batteries of an automobile without materially affecting the sparking current; but of course the motor may be wound for higher voltages.

In the several views, the numeral 1 indicates a diaphragm, 2 a suitable casing in which the diaphragm is held, 3 a shaft extending within the casing substantially in parallelism with the diaphragm, and 4 a suitable casing in which is the electric motor for driving the shaft 3, which may be the armature shaft. Thus, means are provided for driving the rotor at a uniform and comparatively high speed. The arrangements indicated are the same as shown in my co-pending application Serial Number 494,120 filed May 5, 1909, but of course other arrangements may be used. As in that application, the shaft 3, and therefore the rotor 75 may be adjusted toward and from the diaphragm 1, the means to this end herewith illustrated being the same as shown in that application. In accordance with this construction, the casing 4 is movable relatively 80 to the casing 2. The cap of the casing 4 has a sleeve 20 rotatably journaled in the casing 2, and adapted to be held rigid with the casing 2 by a nut 21. The shaft 3 revolves in an eccentric bore in the sleeve 20; 85 so that rotation of the casing 4 and neck 20 adjusts the shaft 3 with relation to the diaphragm.

A resonator or horn 6 adapted to serve as a projector or mouth piece is secured to the 100 casing 2, to be excited by the diaphragm 1. This resonator may be of either of the two forms illustrated in my co-pending application Serial Number 494,120, filed May 5, 1909, or of other suitable form.

The external form of the whole device adapts the signal for use particularly on automobiles, but it may be used as well for launches and other conveyances, and in factories and other places where an alarm is desirable.

Referring now to Figs. 1 to 4, a rotor 7 is secured to the shaft 3 within the casing 2, as by means of nuts 8 or otherwise. Preferably, the periphery of this rotor is provided with a V-shaped groove. 9 is an embodiment of intermittent grip member, here a segmental brake-shoe, preferably V-shaped in cross-section, engaging a portion of the periphery of the rotor. One end of this grip member is connected to the diaphragm, by means of a link 10, and a riveted anchor 11, one end of the link being pivoted to the grip member and the other end to the anchor. A coil tension spring 19 is secured to the other end of the brake segment; and the outer end of this spring is secured to an adjusting screw 12, threaded into an opening in the casing 2. The rotor may be of wrought iron and the grip member of rawhide, or the

rotor may be of amber and the grip member of hard rubber. The body of the rotor may be of metal and the periphery or peripheral surface of amber or other suitable material having the properties already described. The direction of rotation of the rotor is indicated by an arrow. The tension of the diaphragm 1 and of the spring 19 afford the pressure for holding the friction surfaces together. This force is slight compared with the pull of which the grip member is capable while held in intimate gripping contact with the rotor. The grip member moves with the rotor, flexing the diaphragm inward, until the tension of the diaphragm finally equals the tractive effort of the rotor, when the movement of the grip member stops. The relative slip thus produced practically eliminates the friction for the moment, and the grip member slips back under the tension of the diaphragm. The friction surfaces again grip, and the actions are repeated, the movements of the grip member being mechanically transmitted to the diaphragm, causing the latter to vibrate and produce sound. Preferably, the pull of the diaphragm and of the spring are exerted in directions substantially tangential to the periphery of the rotor. The separation of the surfaces at the moment of relative slip may be due in part to the pull of the spring, which as the brake travels around with the rotor tends to pull the end of the brake away from the rotor. The rotor may be driven in the direction opposite to that indicated by the arrow, in which event the travel of the grip member with the rotor is not in opposition to the tension of the diaphragm, but to the tension of a spring such as 19. In this case the diaphragm would be normally bowed toward the rotor. However, the other arrangement is preferred. In general, where desired, the diaphragm may be normally bowed, instead of being normally straight.

In the form of the invention illustrated in Figs. 5 and 6 the grip member 9^a is in the nature of a coil in frictional contact with the shaft 3, which is also the rotor. This coil is preferably of catgut, but may be of other material, as rawhide, having the peculiar frictional properties required. The shaft may be of steel or bronze and may or may not be provided with a sleeve of amber or other suitable material secured rigidly thereto. One end of the coil is connected to an anchor 11^a riveted to the diaphragm, and the other end to an adjustable anchor, shown as consisting of a hook 15 secured to an internally threaded slide 16, which has dovetail engagement with a guide 17 and receives an adjusting screw 18 swiveled in the casing 2. The action here is the same in fundamental principle with that described in connection with the first form of the in-

vention. The grips and slips occur in the same manner. The coil grip member has an oscillating movement, instead of a movement of translation as in the other instance.

In the form of the invention shown in Figs. 7 and 8, the rotor 7^b presents a friction face. Pressed against this face is a grip member in the nature of a disk 9^b. In this form of the invention the diaphragm plays no part in holding the grip member against the rotor. Various yielding or resilient means may be provided for this purpose. A desirable device is a spring yoke 20, which is secured to the casing 2 and presses upon the upper surface of the disk 9^b. The disk 9^b is connected to the diaphragm, as by means of a link 21, which is pivoted at one end of the disk and at the other end to an anchor 11^b riveted to the diaphragm. The rotor 7^b may be of machine steel and the disk 9^b may be of bronze. Or the rotor may be of amber or have an amber surface or facing, and the disk may be of hard rubber. Each friction member is indicated in the drawing as being provided with an applied friction facing. Other suitable materials may be used. The grip and slip action is the same as in the other instances.

In Fig. 9 I have shown how the harshness of sound that would be produced by the means illustrated may be smoothed out by a tuning fork, or other vibration regulator, so as to produce a musical note. For purpose of illustration this development of the invention has been shown applied to the form of the invention shown in Figs. 1 to 4. One tine of the tuning fork 25 is shown pivoted to the link 19. The other tine of the fork is connected to the diaphragm by a link 26, which is pivoted at one end to the fork and at the other end to the anchor 11 riveted to the diaphragm.

In the forms of the invention thus far discussed, the grip member has had closed connection with the diaphragm. However, this is not essential. In Fig. 10 I have shown a loose or one-way connection between the grip member and the diaphragm, whereby the grip member imparts a push only to the diaphragm. For purpose of illustration I have shown such thrust connection as applied to the form of the invention shown in Figs. 7 and 8. Here the disk 9^b is provided with a rigid thrust projection 21^b, which is not secured to the diaphragm. It is obvious that the direction of rotation is reversed, and the thrust member 9^b pushes the diaphragm on each movement of the disk 9^b with the rotor, and jumps away from the diaphragm at each slip. It follows that the connection between the grip member and the diaphragm may be such as to impart pulls only, in other words, a tension connection.

Fig. 12 shows a construction in which the

grip member is secured to or is a part of the diaphragm structure. In the illustrative arrangement shown, a button or projection 9^a is riveted or otherwise secured to the diaphragm and rests against the periphery of the circular rotor 7^d. The contacting surfaces of the two members may be of the same kind of metal, and may be of about the relative smoothness or roughness left by the emery wheel. The rotation of the rotor pulls the resiliently supported grip member 9^a, the grip is quickly released, and the member 9^a jumps or slips back. These movements of the member permitted by the yielding nature of the diaphragm, may be exceedingly slight; but they are sufficient to initiate and maintain vibrations in the diaphragm, and, when the diaphragm is fully actuated, the member 9^a has a considerable range of movement toward and from the periphery of the rotor in accordance with the vibrations of the diaphragm. Each inward vibration strikes the member 9^a against the rotor, a momentary grip ensues, and the member is pulled forward slightly by the rotor, until the slip or separation occurs. These slight grip movements of the member 9^a with the rotor are sufficient to maintain the vibration of the diaphragm and the inward and out movement of the member 9^a. In fact, after the surfaces first grip the action is in the nature of a jam of such force as to produce a very heavy pounding. In the best arrangement of this construction, the point of contact between the member 9^a and the periphery of the rotor 7^d is slightly in front of the radius perpendicular to the diaphragm. The offsetting of the projection 9^a from this radius may be varied from a degree perhaps even greater than that shown substantially to zero, that is, with the point of contact substantially coincident with the radius. If desired the rotor may be provided on its periphery with a "teasing" or vibration-initiating projection 12, in which event the diaphragm projection 9^a need not normally be in contact with the rotor or may be in imperfect contact. This "teasing" projection may be low as compared with the amplitude of vibration of the diaphragm, so that it does not appreciably affect the sound when the diaphragm vibrations have reached their maximum. It will be understood that the first vibrations of the diaphragm are produced by the projection 12 striking the projection 9^a, but that thereafter the vibrations are due to the grip and slip action.

In the several forms of apparatus embodying the invention, the application of the grip and slip action to the diaphragm may be either central or eccentric of the diaphragm. If the diaphragm connection be eccentric a lever action is produced, in that the range of movement at the center of the

diaphragm will be greater than at the eccentric point of application of the force. Thus, with a comparatively slight to and fro movement of the grip member practically any desired amplitude of diaphragm vibration may be produced.

Forms of apparatus employing a light flexible tension connection between the diaphragm and driver, such, for example, as illustrated in Fig. 5, possess certain advantages, in that such a flexible member is comparatively unaffected by wear, and by reason of its slight inertia it may attain high velocity with the expenditure of comparatively little power.

I claim:

1. In an alarm or signal, a friction driver having its operating surface traveling in one direction, means for driving the same, a friction grip member, yieldingly restrained against movement in the direction of travel constantly tending to contact with said driver, the friction surfaces of said driver and grip member being of a nature to grip with exceeding intimacy of contact and great friction and to suffer great diminution of friction upon severance of the union, whereby alternate grips and slips of the grip member are produced, and a diaphragm agitated by the chattering of the grip member for the production of loud sound.

2. In an alarm or signal, a friction driver having its operating surface traveling in one direction, means for driving the same, a friction grip member yieldingly restrained against movement in the direction of travel constantly tending to contact with said driver, the friction surfaces being of a nature to grip with exceeding intimacy of contact and great friction and to suffer great diminution of friction upon the occurrence of relative slip, whereby alternate grips and retrograde slips of the grip member are produced, and a diaphragm having mechanical connection with said grip member so as to be agitated thereby.

3. In an alarm or signal, a friction rotor having its operating surface traveling in one direction, a friction grip member yieldingly restrained in the direction of travel constantly tending to contact with said rotor, the friction surfaces of said rotor and grip member being of a nature to grip with extreme intimacy of contact and great friction and to suffer great diminution of friction upon severance of the union, whereby alternate grips and retrograde slips of the grip member are produced, and a diaphragm arranged to be agitated by the chattering of the grip member for the production of loud sound.

4. In an alarm or signal, coöperating friction members constantly tending to contact with each other having surfaces of a

- high coefficient of friction, means for driving one of said members in one direction in contact with the other, one of said members being yieldingly restrained in the direction of travel and having a chattering action due to alternate gripping and slipping on the other of said members, and a diaphragm mechanically associated with one of said members so as to be agitated by said chattering action.
5. In an alarm or signal, co-operating friction members constantly tending to contact with each other of a nature alternately to grip and slip, means for driving one of said members in one direction, one of said members being resiliently yieldingly restrained in the direction of travel, and a diaphragm associated mechanically with the yieldable member so as to be agitated by the grip and slip action.
10. In an alarm or signal, a friction rotor, a yieldingly restrained friction grip member constantly tending to contact with said rotor, the friction surfaces of said rotor and grip member being of a nature to grip and slip alternately, and a diaphragm associated with said grip member so as to be agitated thereby for the production of loud sound.
15. In an alarm or signal, a friction rotor, a yieldingly restrained grip member constantly tending to contact with said rotor, the friction surfaces of said rotor and grip member being of a nature to grip and slip alternately, and a diaphragm associated with said grip member so as to be agitated thereby for the production of loud sound.
20. 7. In an alarm or signal, a friction rotor, a yieldingly restrained grip member constantly tending to contact with said rotor, the friction surfaces of said rotor and grip member being of a nature to grip and slip alternately, and a diaphragm agitated by said grip member and having mechanical connection therewith whereby a force of increasing effect tends to produce a retrograde slip of the grip member after each grip.
25. 8. In an alarm or signal, a friction driver, means for driving the same, a friction grip member yieldingly restrained in the direction of travel constantly tending to contact with said driver, resilient means holding said driver and grip member together, the friction surfaces being of such nature as to grip and slip alternately, and a diaphragm having mechanical actuating connection with said grip member.
30. 9. In an alarm or signal, a friction driver having its operating surface traveling in one direction, means for driving the same, a friction grip member yieldingly restrained in the direction of travel constantly tending to contact with said driver, the friction surfaces of said driver and grip member of a nature to grip and slip alternately and repeatedly, and a diaphragm having mechanical connection with said grip member whereby it is agitated thereby and controls the grip and slip action thereof.
35. 10. In an alarm or signal, a friction driver having its operating surface traveling in one direction, a friction grip member yieldingly restrained in the direction of travel constantly tending to contact with said driver, the friction surfaces being of a nature to grip and slip alternately, and a diaphragm having mechanical connection with said grip member whereby it is agitated thereby and controls the grip and slip action thereof.
40. 11. In an alarm or signal, co-operating friction members of a nature alternately to grip and slip, means for driving one of said members, one of said members being yieldable in the direction of travel, a diaphragm associated mechanically with the yieldingly restrained member so as to be agitated by the grip and slip action, and a vibrating member interposed in such mechanical connection and adapted to modify the vibration of said diaphragm.
45. 12. In an alarm or signal, a friction driver, a yieldable friction grip member, the friction surfaces being of a nature to grip and slip alternately and repeatedly, a diaphragm connected mechanically with said grip member and a tuning fork interposed in such mechanical connection.

Signed at New York city in the county of New York and State of New York this 6th day of June, A. D. 1910.
